Filed Feb. 24, 1959, Ser. No. 54,725

Term of patent 14 years

(Cl. D4—3)

Fig. 1.

Fig. 2.

Fig. 5

Fig. 3.

Fig. 4

Fig. 1 is a perspective view of the double roll toilet tissue holder, showing my new design;

Fig. 2 is a top plan view thereof;

Fig. 3 is a front elevational view thereof;

Fig. 4 is a side elevational view thereof; and

Fig. 5 is a sectional view thereof taken in the direction of the arrows along the line 5—5 of Fig. 2.

The back of the holder is substantially plain. The other side of the central member is like the side shown.

The dominant features of my new design reside in the portions shown in full lines.

I claim:

The ornamental design for a double roll toilet tissue holder, substantially as shown and described.
